(57) **CLAIM**

The ornamental design for a telephone receiver with a speaker, as shown and described.

DESCRIPTION

FIG. 1 is a front view of a telephone receiver with a speaker embodying our new design;
 FIG. 2 is a top plan view thereof;
 FIG. 3 is a rear view thereof;
 FIG. 4 is a bottom view thereof;
 FIG. 5 is a right side view thereof;
 FIG. 6 is a left side view thereof;
 FIG. 7 is a perspective view of the telephone receiver; and,
 FIG. 8 is a perspective view as viewed from the portion below the telephone receiver.
